MALCOLM C. RORTY, OF PARIS, FRANCE, AND JOHN C. POTTER, OF MADRID, SPAIN,
ASSIGNORS, BY MESNE ASSIGNMENTS, TO WESTERN ELECTRIC COMPANY, INCOR-
PORATED, OF NEW YORK, N. Y., A CORPORATION OF NEW YORK.

TELEPHONE RECEIVER.

Application filed January 5, 1926. Serial No. 79,294.

This invention relates to telephone receivers, and has for its general object the provision of a new and improved structure which is simple in construction, and efficient and satisfactory in operation.

The characteristic features of the invention will be hereinafter described in connection with the accompanying drawing in which is shown a watch-case receiver having 10 the invention embodied therein, although it is to be understood that it may equally well be embodied in receivers of other types.

In the drawing, Fig. 1 is a sectional elevation on a plane passing through the axis 15 of the receiver; and Fig. 2 is a plan view, with the ear-piece portion of the casing removed, showing the internal parts of the receiver.

Referring to the drawing, the internal 20 parts of the receiver are shown as mounted in a casing, made of bakelite or other suitable material, comprising a cup-shaped back portion 5 and an ear-piece 6 of forms clearly shown in the drawing, these parts being secured to one another by cooperating threaded 25 portions indicated at 7. The permanent magnet structure of the receiver comprises an iron or steel cup-shaped portion 9, and an iron or steel mushroom-shaped portion 30 10 which is secured to the middle of the inside of the portion 10 by a screw 12 or in any other suitable manner.

It will be understood that the magnetic flux, due to this permanent magnetic structure, passes across the annular gap between the edge 14 of the mushroom-shaped magnet portion 10, and the edge 15 of the cup-shaped portion 9 of the permanent magnet. This 35 gap is bridged by a pole piece in the form of a soft iron annular cup 17, arranged between the upturned edge 15 of the cup-shaped magnetic portion 9 and the edge 14 of the mushroom-shaped magnetic portion 10, except for the fact that a gap of low 40 magnetic permeability is introduced by means of a ring 18 of brass or other substantially non-magnetic material interposed between the inner upturned edge of the annular cup 17 and the edge 14 of the mushroom-shaped magnetic portion 10. The mushroom-shaped 45 magnetic portion 10, the brass ring 18 and the annular cup 17 are preferably sweated 50

together; and their relations to one another will be understood from Fig. 1. This construction facilitates the accurate determination, by grinding operations, of the distance between the plane of the top face of the mushroom-shaped portion 10, and the plane of the top of the outer edge of the annular cup 17, this being an important matter, as 55 the distance between these planes determines the air gap between the outer edge of the diaphragm 20 and the outer edge of the annular cup 17. The diaphragm 20 is mounted on the flat top of the mushroom-shaped portion 10 of the receiver, and is secured thereto by a cap 21 through which passes a screw 22 which extends through a hole in the center of the diaphragm 20 and enters the threaded hole in the magnet portion 10 60 with which the other end of the screw 12 cooperates. As clearly shown in Fig. 1, the cap 21 is recessed on its bottom, so as to form a downwardly extending flanged edge which cooperates with the diaphragm 20 above the outer edge 14 of the mushroom-shaped magnet portion 10. In this manner, the diaphragm 20 is so held that its edge, and not its center, is free to vibrate. The coil 25 of the 65 wire carrying the talking current is mounted 70 within the soft iron annular cup 17, the ends 26 of said coil being brought out through holes in the annular cup 17, the cup-shaped magnet portion 9 and the back portion 5 of the casing, or being secured to terminals 80 extending from the outside of the casing portion 5 in a well known manner. The coil 25, being of large diameter, can be of com- 75 paratively coarse wire, and still have ade- 85 quate impedance. 90

In the operation of the telephone receiver, the varying magnetic flux, due to the coil 25, swings the magnetic flux, due to the permanent magnetic structure, back and forth across the gap introduced by the brass ring 18 and the air gap between the outer edge of the annular cup 17 and the edge of the dia- 95 phragm 20. This, of course, causes the edge of the diaphragm 20 to vibrate, with consequent production of sound waves. 100

It will be apparent that the receiver structure which forms the subject of this invention, is highly efficient because the magnetic flux due to the permanent magnetic struc-

ture is swung back and forth, and is not directly opposed and strengthened by the flux due to the coil 25, as in the usual type of receiver; and also because the edges of the 5 diaphragm have naturally a very high pitch thus giving a satisfactory quality to the sound waves produced.

While only one form of the invention has 10 been illustrated, it is to be understood that it 15 may be embodied in other forms and construction of telephone receiver, without departing from the spirit of the invention as defined in the claims hereto appended.

Having described the invention, what is 15 claimed is:

1. In a telephone receiver, a permanent magnet structure providing an annular gap, a soft iron pole piece located in said annular gap, a coil cooperating with said pole piece, 20 and a diaphragm rigidly supported at its central portion and having its edge extending into cooperative relation with said pole piece.

2. In a telephone receiver, a permanent 25 magnet structure providing an annular gap, a soft iron annular cup cooperating with said magnet structure and located in said annular gap, a coil located in said annular cup, and a diaphragm rigidly supported at 30 its central portion and having its edge extending into cooperative relation with said annular cup.

3. In a telephone receiver, a permanent 35 magnet structure providing an annular gap, a soft iron annular cup located in said gap and cooperating with said permanent magnet structure, a spacing member of substantially nonmagnetic material interposed between one edge of said annular cup and said 40 magnetic structure, a diaphragm rigidly secured at a central portion to said magnetic structure and having its edge in cooperative relation to the other edge of said annular cup, and a coil located in said annular cup.

4. In a telephone receiver, a permanent 45 magnet structure comprising a cup-shaped member and a mushroom-shaped member secured to the center of said cup-shaped member, a soft iron annular cup located in the 50 annular space between said magnet members, a coil located in said annular cup, a diaphragm extending over the top of said mushroom-shaped magnet member and in

cooperative relation to one edge of said annular cup, and means for rigidly securing 55 the central portion of said diaphragm to said mushroom-shaped magnet member.

5. In a telephone receiver, a permanent 60 magnet structure comprising a cup-shaped member, and a mushroom-shaped member secured to the center of said cup-shaped member, a soft iron annular cup located in the annular space between the edges of said 65 magnet members, a diaphragm extending over the top of said mushroom-shaped member and in cooperative relation to the outer edge of said annular cup, a cap extending over the central portion of said diaphragm, and means for securing said cap to said mushroom-shaped member in clamping engagement with said diaphragm.

6. In a telephone receiver, a cup-shaped 70 permanent magnet, a plurality of annular magnetic poles for said magnet, a coil for said poles, a diaphragm, and means for supporting said diaphragm so that the periphery thereof is free to vibrate.

7. In combination, a circular magnet, a channel-shaped circular member, the flanges of which serve as magnetic poles for said magnet, a coil positioned between the flanges of said member, and means for supporting said diaphragm at points removed from its periphery, so that the periphery is free to vibrate.

8. In combination, a magnet, a diaphragm, a circular supporting member therefor of smaller diameter than said diaphragm and forming one pole of said magnet, and an annular channel-shaped member, the flanges of said member constituting poles of opposite polarity to that of said circular member and a coil in said channel.

9. In a telephone receiver, a circular magnet, a vibratile member, supporting means for said member, said means constituting one pole of said magnet and an annular-shaped member, portions thereof forming magnetic poles, said poles being spaced relative to said vibratile member and said supporting means to form parallel flux paths.

In testimony whereof we have affixed our signatures to this specification.

MALCOLM C. RORTY.
JOHN C. POTTER.
